US00D702645S

(12) **United States Design Patent** (10) **Patent No.:** **US D702,645 S**
Hori et al. (45) **Date of Patent:** **** Apr. 15, 2014**

(54) **CONNECTOR PLUG**

(71) **Applicant:** **Nintendo Co. Ltd.**, Kyoto (JP)

(72) **Inventors:** **Yuji Hori**, Kyoto (JP); **Hitoshi Tsuchiya**, Kyoto (JP); **Naoya Yamamoto**, Kyoto (JP); **Masato Ibuki**, Kyoto (JP); **Akiko Suga**, Kyoto (JP); **Kenichiro Ashida**, Kyoto (JP); **Hiroki Ikuta**, Kyoto (JP); **Fumiyoishi Suetake**, Kyoto (JP); **Junji Takamoto**, Kyoto (JP); **Shinji Yamamoto**, Kyoto (JP); **Takafumi Nishida**, Kyoto (JP)

(73) **Assignee:** **Nintendo Co., Ltd.**, Kyoto (JP)

(**) **Term:** **14 Years**

(21) **Appl. No.:** **29/438,838**

(22) **Filed:** **Dec. 4, 2012**

(30) **Foreign Application Priority Data**
